UNITED STATES PATENT OFFICE.

WILLIAM J. SHARP, OF YORK, PENNSYLVANIA.

DESIGN FOR A GAME-BOARD.

SPECIFICATION forming part of Design No. 35,083, dated September 10, 1901.

Application filed August 9, 1901. Serial No. 71,535. Term of patent 7 years.

To all whom it may concern:

Be it known that I, WILLIAM J. SHARP, a citizen of the United States, residing at 949 North George street, York, in the county of York and State of Pennsylvania, have invented and produced a new and original Design for a Game-Board, of which the following is a specification, the construction being illustrated in the accompanying drawings.

10 My invention is a design for a game-board; and it consists in the shape and configuration illustrated in the accompanying drawings, in which—

Figure 1 is a plan view of a game-board embodying the design, and Fig. 2 is a vertical section on the line 2 2 of Fig. 1.

The reference-numeral 1 designates the board, which is round and formed with a continuous vertical peripheral flange 2.

20 3 designates a straight centrally-disposed flange from the upper end of which diverge oppositely-curved flanges 4 and 5, joining the edge flange 2. Parallel to the central flange

3, on opposite sides thereof and at equal distances therefrom, are vertical flanges 6 and 7. 25 From the points 8 these flanges are curved to form semicircles 9 and are then converged to form oppositely-inclined portions 10. The outer sides of the inclined portions 10 of the flanges 8 are joined to the peripheral 30 flange 2 by oppositely-curved vertical flanges 11 and 12.

The leading features of the design are the central vertical flange and its diverging ends and the parallel vertical flanges having the 35 peculiar shape and contour shown.

I claim—

The design for a game-board herein shown and described.

In testimony whereof I affix my signature 40 in presence of two witnesses.

WILLIAM J. SHARP.
